United States Patent Office.

B. M. HALL OF SOUTH BEND, INDIANA.

Letters Patent No. 67,755, dated August 18, 1867.

GRAINING MACHINE.

The Schedule referred to in these Letters Patent and making part of the same.

TO ALL WHOM IT MAY CONCERN:

Be it known that I, B. M. HALL, of South Bend, in the county of St. Joseph, and State of Indiana, have invented certain new and useful Improvements in Graining Machines; and I do hereby declare that the following is a full and complete description of the construction and operation of the same, reference being had to the accompanying drawings, making a part of this specification, in which—

Figure 1 is a side view of the machine.

Figure 2 is a top view of the same.

Figure 3 is an end view.

Like letters of reference refer to like parts in the views.

A, fig. 1, is a light frame, in which are arranged the gearing B B', fig. 3, and rollers C, D, and E, fig. 2, all the shafts of which have their bearings in the sides of the frame. Passing around the several rollers is an endless belt or apron, G, which consists of rubber, gutta percha, cloth, leather, or any other suitable material, on which is engraved or stamped any appropriate design for graining. This apron is drawn tight upon the rollers by the ends of the frame being made adjustable, so that they may be extended by means of the screws I. It will be seen that the extreme ends I' are attached to the frame by a lap-joint, J, as shown in fig. 1, a slot being cut through the end of the frame for the accommodation of the sliding of the screw when the attached ends are being extended. K, fig. 1, is an adjustable journal-box, by the means of which the rollers L are forced against the feed-roller C by the thumb-screw M. A spring may be introduced for this purpose if so desired. By this arrangement of gearing and rollers it will be evident that on turning the gearing by the crank N the pressure of the rollers L upon the feed-rollers C, and between which the edges of the apron pass, will carry the apron around over the rollers, and thus change the position of the apron to any degree required by turning the crank more or less. The design on the apron being properly supplied with the paint or coloring material, is then transferred to the pail, tub, or other work to be grained, by holding and pressing the apron against it, the under side of the frame being made curving, in order to adapt it to the curve of the work. One impression having been taken, another of a different design may then be given by simply turning the apron. By this means the design transferred may be slightly varied or wholly changed by turning the machine more or less, as the nature of the engraving or design on the apron may determine. The roller E is intended as a wiper, for the purpose of removing all surplus coloring material, and for diffusing it more equally over the apron, and thus making the transfer more uniform in depth of color and order. This wiper is driven by the belt O passing from the pulley P. The apron can be readily taken from the machine, and others substituted of different designs, by simply drawing the screws from the cross-ties R, by which the sides of the machine are held together. This allows the side to be removed, so that the apron can be taken off and another put on in its place, and thus any number of aprons and of different designs may be used, as the nature of the work may require.

What I claim as my improvement, and desire to secure by Letters Patent, is—

1. The rollers C, D, E, and apron G, as arranged in combination with the frame A, provided with the adjustable ends I', in the manner and for the purpose substantially as described.
2. The arrangement of the gearing B B' and rollers L, in combination with the rollers C D E, and apron G, as and for the purpose set forth.

B. M. HALL.
